CHILD'S CAR SEAT TOY

Perce R. Christians, Sioux City, Iowa

Application May 25, 1955, Serial No. 36,198

Term of patent 14 years

(Cl. D14—6)

FIG. 2

FIG. 3

FIG. 4

Fig. 1 is a fragmentary top perspective view of a child's car seat toy, showing my new design;

Fig. 2 is a fragmentary top plan view thereof;

Fig. 3 is a side elevational view thereof; and

Fig. 4 is a fragmentary bottom perspective view thereof, to a reduced scale.

A portion has been omitted from Figs. 1, 2 and 4 for convenience of illustration.

I claim:

The ornamental design for a child's car seat toy, as shown and described.
